UNITED STATES PATENT OFFICE

CARL V. POHLSON, OF PAWTUCKET, RHODE ISLAND

COMBINED BRUSH AND HAT HOLDER

Application filed March 26, 1930. Serial No. 439,011.

This invention relates to a combined brush and hat holder; and has for its object to provide a device for supporting a hat which will also serve as an attractive ornament when not supporting a hat, the device being also provided with a brush shaped to assist in the support of the hat and also adapted for use in cleaning the hat or other garment.

A further object of the invention is to so mount the brush on the standard that the same may be readily removed from the standard to be used independently thereof, if desired for cleaning purposes.

A still further object of the invention is to so shape the bristles of the brush and the body portion of the brush that they will combine with the standard and base portions to complete the design and produce the ornamental effect desired.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a view showing my improved holder partly in section and illustrating a hat in dotted line as supported thereon;

Fig. 2 shows the brush as having been removed from the standard and its body portion grasped by the hand of the operator to be manipulated for cleaning purposes independently of the standard;

Fig. 3 shows the standard as being inserted into the body of the brush in such position as to cause the bristles of the brush to stand upwardly.

It is found in practice in the display or support of hats for home or other use of advantage to so form the display stand that they will be handsome and attractive and serve as an ornament even when the hats are removed therefrom; and it is also found of advantage to mount a brush on the free end of the hat supporting standard in such a position that it may assist in forming a support for the hat and also to be used as a brush for cleaning the

hat or other garment when desired. It is also found in practice of advantage to so mount the brush upon the standard that it may be readily removed therefrom to be used independently of the standard if desired for cleaning purposes, and to so shape the body of the brush that it will also serve as a convenient handle to be grasped by the hand of the user. It is also found of advantage to provide a supporting sleeve for the lower end of the more or less delicate standard, which sleeve is shaped to conform with the ornamental design of the device; and the following is a detailed description of the present embodiment of my invention and showing one construction of holder by which these advantageous results may be accomplished.

With reference to the drawings, 10 designates the base of the holder, which may be made of wood or other suitable material and of sufficient size and weight to support the hat when mounted on its standard. On this base, I have mounted a standard 18 which extends upwardly the desired distance. A brush 12 is provided having a body portion 13, preferably in spherical shape, the same being drilled to receive the desired number of radiating bristles 14 disposed to represent a thistle, also this body is herein shown as being drilled at 15 to receive the free end 16 of the standard 18.

This standard is preferably loosely mounted in the brush body so that the brush may be readily removed therefrom to be used independently of the standard if desired, or in some instances the body of the brush may be drilled at a point opposite the bristles, as illustrated in Figure 3, and permanently secured in this position so that the standard may be employed as a handle for the manipulation of the brush.

In some instances instead of attaching the lower end of the standard in the base 10, I may insert a standard supporting an ornamental sleeve 17 in the base 10 and then insert the end 18 of the standard into this member 17 to be either fixedly or removably mounted therein as desired.

My improved hat holder is very simple and

inexpensive in construction, is very ornamental in appearance and by the arrangement of the brush on its upper end, this brush is caused to perform a double function; first, to serve as a support for the hat, and second, it serves as a cleaner for the hat or other garment.

While I have described certain construction forms which embody the principles of my invention, it is obvious that other desired changes in arrangement may be made within the spirit and the scope of the invention as defined in the appended claims.

I claim:

- 15 1. A combined brush and hat holder comprising a base, a standard supported by the base, and a brush supported on the standard provided with a portion arranged to support a hat.
- 20 2. A combination brush and hat holder comprising a base, a standard supported by the base, and a brush removably supported on the standard, said brush being provided with a portion arranged to support a hat when in position on the standard.
- 25 3. A combination brush and hat holder comprising a base, a standard supported by the base, and a brush having a body portion with an opening therein to receive the end of the standard.
- 30 4. A combined brush and hat holder comprising a base, a standard supported by the base, a brush having a body portion with a hole therein for removably receiving the free end of the standard, the body portion of the brush when mounted on the standard being arranged to support a hat and said brush being adapted for independent use when removed from the standard.
- 35 40 5. A combined brush and hat holder comprising a base, a standard supported by the base, a brush provided with a body portion shaped to form an operating handle, said body having a hole therein shaped to removably receive the free end of said standard.
- 45 6. A combined brush and hat holder comprising a base, a standard supported by the base, a brush provided with a body portion shaped to form an operating handle and also to serve as a support for a hat, said body having a hole therein for removably receiving the free end of said standard.
- 50 55 7. A combined brush and hat holder comprising a base, a sleeve supported in the base, a standard supported in the sleeve, and a brush supported on the standard provided with a portion arranged to support a hat.

In testimony whereof I affix my signature.

CARL V. POHLSON.
